UNITED STATES PATENT OFFICE

162,963

ROSARY

Arthur B. Kimball, Newtonville, Mass.

Application October 25, 1950, Serial No. 12,725

Term of patent 14 years

(Cl. D45—16)

To all whom it may concern:

Be it known that I, Arthur B. Kimball, a citizen of the United States, residing at Newtonville, in the county of Middlesex and Commonwealth of Massachusetts, have invented a new, original, and ornamental Design for a Rosary, of which the following is a specification, reference being had to the accompanying drawing, forming a part thereof, in which:

Fig. 1 is a plan view of a rotary, showing my new design, and

Fig. 2 is an edge view of the crucifix.

The dominant feature of my design for a rosary resides in the specific sword-shaped cruci-

fix element depending therefrom in inverted position as shown.

I claim:

The ornamental design for a rotary, as shown and described.

ARTHUR B. KIMBALL.
